CONVERTIBLE LAND AND WATER CRAFT

Wilbur I. Thelen, Grand Ledge, Mich., assignor to Arthur Thelen, Fowler, Mich.

Application March 24, 1955, Serial No. 35,183

Term of patent 14 years

(Cl. D71—1)

The essential features of my design reside in the portions shown in full lines.

I claim:

The ornamental design for a convertible land and water craft, as shown and described.
